STEAM TREATMENT

Filed Oct. 16, 1929

FIG. 1

FIG. 2

FIG. 3

INVENTOR
Charles E. Lucke
BY
Amory Beale
ATTORNEY

UNITED STATES PATENT OFFICE

CHARLES E. LUCKE, OF NEW YORK, N. Y., ASSIGNOR TO THE BABCOCK & WILCOX COMPANY, OF BAYONNE, NEW JERSEY, A CORPORATION OF NEW JERSEY

STEAM TREATMENT

Application filed October 16, 1929. Serial No. 399,908.

This invention relates to steam treatment, and an object of this invention is to provide a method of and apparatus for conditioning steam, of such character, that the degree of moisture in the steam can be accurately controlled, or entirely eliminated, or any desired degree of superheat be imparted to the steam. The term "conditioning", as herein employed, may mean the conversion of wet steam to less wet, of wet steam to dry, the conversion of wet or dry steam to superheated steam, or an increase in the degree of superheat.

When moisture carrying scale forming impurities, is evaporated by the application of heat to the outside of a vessel containing steam having such moisture in suspension, those particles of moisture in contact with the confining wall deposit the impurities upon the surface of the wall at the time of vaporization, with the result that a heat insulating layer of scale is formed on the inner surface of the confining wall. This layer of scale interferes with the absorption of heat by the water or steam with the result that the confining wall burns away.

A further object of this invention is to provide a method and apparatus for drying saturated steam in such a way as to prevent the formation of scale upon a confining wall.

These and other objects which will be apparent to those skilled in this particular art are accomplished by means of the invention illustrated in the accompanying drawing, in which Fig. 1 is a diagrammatic view of a portion of a boiler furnace, provided with a steam conditioning device constructed in accordance with one embodiment of this invention; and Figs. 2 and 3 are transverse sectional views of a certain detail of construction showing different modifications thereof.

Although the present invention is shown in connection with a fuel fired steam generating boiler, for the purpose of conditioning steam formed in such a boiler, it will be readily understood that the invention is equally applicable to the conditioning of steam entirely independent of any particu-

lar steam source, and might be employed, for example, in place of a reheatere.

This invention contemplates the conditioning of a body of steam by introducing a heating or drying fluid to the interior of the body of steam, in such a way as to secure a thorough mixing action. This conditioning fluid, which in the illustrative embodiment is superheated steam but may, obviously, be other mediums, delivers the steam conditioning heat to the body in such a way that any moisture, as when the steam being conditioned is saturated, is vaporized in suspension, so that any scale forming impurities remain in the body of steam as suspended dust and do not adhere to the confining wall.

The particular embodiment of the present invention which has been chosen for the purposes of illustration, includes a device for eliminating all moisture from saturated steam during its travel from a steam and water drum to the superheater, with the result that only dry steam enters the latter. The drying of the body of saturated steam is accomplished by applying the vaporizing heat to the body internally and away from the confining surface. In this way, vaporization of water carrying scale forming impurities in contact with the walls of the superheater is avoided, so that no scale is deposited upon such walls.

As illustrated, the present invention is shown in connection with a boiler furnace 1, having any desired form of steam generating boiler 2 associated therewith. A connection 3 is provided for conveying saturated steam from the steam space of a steam and water drum 4, to the inlet header 5 of a superheater 6, which is illustrated in the form of a plurality of bent tubes connecting the inlet header with the outlet header 7. A connection 8 is provided for carrying the superheated steam to the pipe line 9, which in turn conveys it to any desired point of consumption.

This invention is particularly applicable to such an arrangement for the purpose of preventing the deposition of scale in the superheater tubes, by eliminating all scale bearing moisture from the body of saturated

steam flowing to the superheater and prior to its introduction thereto. This is accomplished by introducing the conditioning fluid to the interior of the stream of saturated steam in such a way as to obtain a thorough mixing of the two fluids.

In the illustrated arrangement, where the conditioning fluid is superheated steam, a pipe connection 10 leads from the superheated steam outlet connection 8, to the inlet of the steam circulator, such as a compressor or blower 11, which is employed to overcome the drop in pressure of steam flowing through the superheater and to establish the desired pressure in the pipe connection. A steam circulator outlet is connected by a line 12 with the saturated steam line 3 at a point between the steam and water drum 4 and the superheater inlet header 5, for the purpose of delivering a regulatable amount of superheated steam to the interior of the body of saturated steam flowing to the superheater. The amount of superheated steam used for this purpose is so controlled as to obtain the desired conditioning effect upon the saturated steam so that the latter is either converted from wet steam to dry or has a certain degree of superheat imparted to it. Preferably, a certain amount of superheat is imparted by the conditioning device. When this is done, the amount of superheated steam recirculated by the steam circulator 11, and hence the amount of steam conditioning heat delivered to the saturated steam, is controlled by the degree of superheat in the steam entering the superheater header 5.

As illustrated, this is accomplished by means of a thermostat 13, inserted in the line 3, near the header 5 and connected to a thermostatically operated valve located in the line 10 such as is well known in the art and which may be of any desired construction. It will be apparent that operation of the valve 14 in accordance with the temperature of the steam entering the superheater, will control the amount of steam delivered to the circulator 11, and by it returned to the saturated steam line 3.

It will also be apparent that, assuming substantially constant pressure conditions in the steam and water drum 4, any change in the condition of the steam entering the superheater tubes will result in a corresponding and proportional change in the condition of the steam at the superheater outlet. In this way, the illustrated embodiment of the present invention provides a simple and automatic control of steam conditions at the superheater outlet. Similarly, when the thermostat 13 has been set, in consideration of a definite pressure of saturated steam, any change in the latter must be compensated for by a proper readjustment of thermostat. The particular form of mechanism em-

ployed for injecting the superheated steam into the line 3 may be of any desired construction. As illustrated in Fig. 2, a standard form of Venturi tube is inserted in the line 3 and the return pipe 12 terminates in a nozzle 16 for delivering the superheated steam at the mouth of the venturi.

As illustrated in Fig. 3 an annular form of venturi is used. The pipe connection 12 terminates in a nozzle 17 surrounded by a conical block 18, and delivering the conditioning fluid to the space between the block and a centrally positioned cone 19 in the line 3 for reducing the friction of flow and at the same time obtaining a thorough mixing action. The Venturi tubes permit obtaining a high velocity flow, resulting in a zone of turbulence at the point where the conditioning fluid is introduced, and a return to high pressure without an over all loss of pressure. This turbulence causes the desired thorough molecular mixing of the fluids. At the same time, the Venturi throat has a tendency to cause any particles of moisture flowing along the wall of line 3 to be sprayed off and embodied in the flowing stream so as to be subjected to the conditioning action.

It will be apparent that the present invention provides a simple but effective arrangement for conditioning a body of steam so as to produce a desired degree of wetness or a desired degree of superheat at will.

Although I have described a particular mode of operation, as carried out by a specific form of apparatus, it will be apparent that various changes, additions, omissions, and substitutions may be made therein without departing from the spirit of this invention or the scope of the appended claims.

What I claim is new and desire to secure by Letters Patent is:

1. The combination with a steam boiler having a steam and water drum and a superheater connected to said drum of means for delivering a portion of the steam from the said superheater to the stream of saturated steam flowing from said drum to said superheater, and means for controlling the operation of said first named means in accordance with the degree of superheat.

2. The combination with a steam boiler having a steam and water drum and a superheater connected to said drum, of an outlet for superheated steam from said superheater, a connection for returning superheated steam from said superheater to the saturated steam flowing to said superheater from said drum, a circulator in said connection, a valve for controlling the amount of steam flowing through said connection and means for opening and closing said valve in connection with variations in the temperature of steam entering said superheater.

3. In apparatus of the class described, a steam superheater, a steam inlet line con-

ducting steam to the superheater, an outlet line conducting steam from the superheater, a by-pass line conducting superheated steam from the outlet line to the inlet line whereby
5 the superheated steam mingles with the steam entering the superheater, a pump in the by-pass line for boosting the flow in that line, and a valve in the by-pass line for controlling the weight of superheated steam passing
10 to the inlet line, said by-pass line returning only a part of the superheated steam to flow again through the superheater while superheated steam is flowing through the outlet line to a point of use.
